DISPENSING CONTAINER

Percy M. Thorn, New Rochelle, and Alexander C. Parlini, Woodside, N. Y., and Heinz Becker, Ridgewood, and Eugene Hascher, Newark, N. J.; said Parlini, said Becker, and said Hascher, assignors to said Thorn

Application August 10, 1938, Serial No. 224,218

28 Claims. (Cl. 221—60)

This invention relates to improvements in dispensing containers.

It is an object of this invention to provide a new and improved dispensing container for plastics which will dispense the contents by a single movement with the opening of the container, and more particularly to provide such a container having a top which is openable by rotation in which the rotation of the top for opening purposes may be utilized to expel the contents.

It is a further object to provide a container of the character described which will permit opening and closing of the dispenser without twisting the bag and which nevertheless will permit the same movement to twist the bag to dispense the material after the opening movement is completed.

It is a further object to provide a device of the character described which will insure that twisting of the bag in the act of dispensing will start at the bottom thereof and progress upwardly completely emptying the bag as it goes.

It is a further object to provide a container with a tightly closed top to insure against leakage of material.

It is a further object to provide a means for securely holding the bag to the top of said container.

It is a further object to provide a single and economical means for constructing the container and top.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description, taken in connection with the accompanying drawings, in which:

Figures 1 and 2 are plan views showing the shutter open and closed respectively.

Figures 3 and 4 are sections on the lines III—III and IV—IV of Figures 1 and 2.

Figure 5 is a section on the line V—V of Figure 7.

Figure 6 is a section on the line VI—VI of Figure 8.

Figures 7 and 8 are broken elevation views showing ratchet arrangement to open and close the shutter respectively.

Figure 9 is a cross section of the bag holders shown in Figures 3 and 4.

Figure 10 is an elevation of the bag holder shown in Figures 3 and 4.

Figure 11 is a plan view showing a modified form of the device.

Figure 12 is an elevation partly in section of 5 the same.

Figure 13 is a section on the line XIII—XIII of Figure 14.

Figure 14 is a side elevation of the device shown in Figures 11 and 12 with parts broken away to 10 show holder.

Figures 15 and 16 are sections on the lines XV—XV and XVI—XVI of Figures 17 and 18 respectively.

Figures 17 and 18 are elevations, parts being 15 broken away, showing the ratchet arrangement when the shutter is open and closed respectively.

Figure 19 is a plan view of a modified device.

Figure 20 is a section on the line XX—XX of Figure 19. 20

Figure 21 is a section on the line XXI—XXI of Figure 22.

Figure 22 is a section similar to Figure 20 but after material has been dispensed.

Figure 23 is a plan view of a modified form 25 of the device.

Figure 24 is a bottom view of the same.

Figure 25 is a side elevation of the device shown in Figure 23 partly in section with the shutter in a closed position.

Figure 26 is a central section with the shutter closed.

Figure 27 is a section on the line XXVII—XXVII of Figure 28.

Figure 28 is a section on the line XXVIII—XXVIII of Figure 27. 35

Figure 29 is a plan of the bag holder.

Figure 30 is a section on the line XXX—XXX of Figure 29.

Figure 31 is a side elevation, partly in section, 40 of a further modification of the bag holder.

Figure 32 is a section on the line XXXII—XXXII of Figure 31.

Figure 33 is a view similar to Figure 32 showing a modified form of a bag holding device. 45

Figure 34 is a section on the line XXXIV—XXXIV of Figure 33.

Figure 35 is a view similar to Figure 33 showing a further modification.

Similar numerals refer to similar parts 50 throughout the several views in the forms illustrated.

The device consists in some of its aspects primarily in a container which may be varied in volume to discharge its contents and a closure 55

attached to said container to close the same, so coordinated as to change the volume by the same movement. Within the broad aspects of the invention any suitable form of closure may be coordinated and combined with different forms of containers having various systems by which the volume may be changed. For example a solid container may be provided with a piston or a flexible tube container may be squeezed or rolled.

10 We have chosen for illustration, however, a container of the flexible tube variety in which the volume is decreased by twisting the tube.

This device as illustrated, therefore, in Figures 1 to 10 comprises primarily a container tube 15 40 of flexible material closed at the lower end as shown at 41, having at its upper end a ring or cup shaped member 42, carrying a closure member or cap 43, the ring and closure member cooperating to form a closure for the top of the container.

20 This container, within the broader aspects of this invention, may be made of any material resistant to the plastic contained within the tube, and soft enough to permit twisting to expel the 25 contents—as for example aluminum foil, tinfoil or the like, or paper or Cellophane. We have found, however, that great advantages can be obtained by using a commercial product known as "Pliofilm" which has unique properties which render 30 it especially suitable for use in this invention and which make certain phases possible. It is more elastic than paper or Cellophane and on this account can be made into a tight joint with metal more easily and it is self-welding and 35 molding under moderate heat which assists in closing the lower end of the tube.

The device also contemplates some means for twisting the bottom or lower end 41 of the container so coordinated with the movement of the 40 cap 42 that when the cap is moved to open the closure the lower end 41 is twisted to expel the tube contents. For this purpose there is provided a casing 44 rotatable relative to the ring 42. This casing may have a closed bottom 45. 45 This casing preferably has a bead 46 near its open end and the ring 42 has a cylindrical flange 47 fitting over the end of the casing and rotatable thereon. A bearing is provided to take the end thrust of the ring on the casing which may 50 be accomplished either by having the edge of the flange 47 fit against bead 46 or by providing a shoulder 48 on the ring which may bear against the end of the can. As illustrated both such bearings are provided.

55 The upper end of the container 40 is fitted within the reduced portion 49 of the ring 42 and is held within that reduced portion by a clamping ring 50 which, as shown, can be fitted within the reduced portion in the position shown in 60 dotted lines in Figure 3, and then dished in the opposite direction thus expanding its diameter and forcing the upper end of the container firmly against the wall of the ring.

Any convenient type of closure may be used 65 but we prefer one which is opened and closed by partial rotation of the closure member since with such a closure the twisting of the tube may be directly geared to the closure member. We have therefore chosen the following construction for 70 illustration.

The closure member 43 is in the form of a cap having cylindrical side walls 51 adapted to extend downwardly over the ring 42 and be crimped over the bead 46 to hold the ring and cap rotatably in place. The ring and cap have open-

ings 52 and 53 which in one position are in registry to open the container and are adapted to be closed either by being brought out of registry as in one familiar form of closure having the openings eccentric or by a shutter as here 5 illustrated. In this embodiment the ring 42 has upon its flat face 54 an upwardly pressed pin 55 and the cap 43 has a flat face 56, a downwardly pressed pin 57. A shutter 58 has a slotted opening 59 in one end to receive pin 55 and an opening 60 in the other end to receive the pin 57. The shutter also has an opening 61 in position to be brought into or out of registry with openings 52 and 53 in the familiar manner. The face 54 is provided with a recess to receive a circular washer 62 and the face 56 may be depressed at the center if desired, as shown.

The lower closed end 41 of the container is connected to the casing 44 in a manner to permit the casing to rotate the end 41 but to allow the 20 end to yield as the container is shortened by the twisting. For this purpose there is provided as shown in Figures 1 to 4 within the casing 44 a follower 63 having a central opening 64 through which the end 41 may be carried and a second 25 eccentric opening 65 through which it may be carried back and clamped. The follower as illustrated has a plurality of depending arms 66 adapted to bear against the inside walls of the casing.

If the length of the container be not too great, the lower end may be attached directly to the bottom of the casing, due to the elasticity of the Pliofilm.

Where the casing is made of sheet metal it will 35 be provided with a seam 67 (see Figure 9) against which an arm 66 may engage to prevent rotation of the follower, but to permit the latter to slide upwardly in the casing.

With this construction it will be clear that as 40 the ring 42 is completely sealed within the cap 43 means must be provided to rotate it. This may be accomplished by the limit of relative movement which the shutter type closure affords or by a limiting stop if another type closure is 45 used.

For many purposes it is desirable that the twisting of the tube shall not start until the closure is completely open and that no reverse movement shall be permitted. A practical means 50 for achieving this is as follows.

The upper end of the casing 44 is depressed as shown at 68 to form a ratchet and mounted on the inner face of the cylindrical flange 47 are provided two sets of pawls 69 and 70 preferably 55 extending in opposite directions. These pawls may be cut from the metal of the flange if desired. One of these sets of pawls 69 is spring pressed inwardly to engage the ratchet 68 to prevent relative rotation which would untwist the 60 tube. The other set of pawls 70 is spring pressed away from the ratchet and pressed inwardly by a cam 71 on the inside of the wall 51. This cam 71 is so constructed as to hold the pawl 70 against the ratchet at all times except when the closure 65 is open. As shown it comprises a circumferential indentation in alignment with pawls 70 broken at 72 to permit the pawl to spring outwardly as shown in Figure 5 to free the ratchet.

The form of the invention disclosed in Figures 70 11 to 14 is generally similar to that formerly described. In Figure 11 is shown a different type of opening and in Figures 12, 13 and 14 is shown a different type of follower comprising generally a C shaped member 75 generally arranged to con-

tact the inner face of the casing on three lines of contact, one of which comprises one of the ends 76 in position to contact the edge of the seam 77 of the casing.

5 The lower end 78 of the container 79 may be doubled back upon itself and carried by a clamping sleeve 80 forced into an opening 81 in a bridge member 82 carried by the C shaped member.

10 In the form of the invention shown in Figures 15 to 18 inclusive the flange 47a of the ring 42a is carried down and crimped over the bead 46a so as to be independently held on the casing and the side wall 51a of cap 43a is crimped over 15 the flange 47a. In this manner an appreciable friction may be created between the ring 42a and the casing and the friction between the two pairs of members may, if desired, be independently adjusted so that the parts may be made to 20 operate on a difference in friction between the parts without the need of employing the ratchet and pawls previously described.

For purposes of illustration, however, we have chosen to show the ratchet and pawls also.

25 In Figure 12 the container is shown as completely collapsed.

The form of the invention shown in Figures 19 to 22 shows a different method of attaching the container to the ring—the ring is provided 30 with an upstanding V shaped crevice or groove 83 into which the open end of the container is carried. Thereafter this groove is rolled over as shown in Figures 20 and 22 to crimp the end of the container. This groove will be situated 35 above the shoulder 84 which rests on the top of the casing and below or not above the face 85 corresponding to the face 54 of Figures 1 to 10.

In this illustration, moreover, the follower comprises a bridge 86 extending through slots 87 in 40 the side wall of the casing and bent over against the side walls as shown at 88. This bridge carries a flat portion having strips with inclined ends which are clamped around the closed end of the container. If desired the outer face of the casing 45 may be covered with a paper label which can be cut by the bridge 86 as it rides upwardly.

Figures 23 to 30 show a modified form of the device in which the casing 90 is non-circular in form, affording a compartment 91 at one side in 50 which a tooth brush 92 or other implement may be carried. The top is, however, circular where a rotating cap is employed.

The follower comprises an irregular C shaped member 93 engaging the sides of the casing and 55 made non-rotatable by reason of the non-circular form of the casing. This C member carries a bridge 94 similar to the bridge of Figure 14.

In this embodiment the ring 95 has a flange 96 crimped around a bead 97 and within this 60 flange is a downwardly extending wall 98 against which the upper end of the container is held by a ring 99.

The cap 100 fits on and has its bearings on the outside of the flange 96 affording the possibility of independently adjusting the friction 65 between the pairs of elements as has been previously described. In this view no ratchet mechanism is employed, the friction between the ring and casing being greater than that between the 70 cap and ring so that a rotation of the cap will not twist the container until the cap and ring positively engage each other.

The form of the invention disclosed in Figures 31 to 35 is designed primarily to permit the use 75 of a paper casing. In this form the follower 101

is provided with legs 102 having trailing sharp teeth that readily slide upwardly over the surface of the paper but dig into the paper to resist any side slipping. In Figure 32 the central opening 103 is adapted to have the lower end 5 of the container thrust through it and then grip the same. To this end the central portion is provided with inwardly extending spring arms 104.

In the construction of Figure 33 the follower 10 is provided with a bayonet slot 105 into one end 106 of which the container end 107 may be easily inserted and then forced into and clamped within a narrower portion 108.

In Figure 35 the follower is provided with two 15 spring tongues 109 having cut out between them an elongated hole 110 into which the doubled end of the container may be thrust and clamped.

Since certain changes may be made in the above construction and different embodiments 20 of the invention could be made without departing from the scope thereof, it is intended that all matter contained in the above description or shown in the accompanying drawings shall be interpreted as illustrative and not in a limiting 25 sense.

It is also to be understood that the following claims are intended to cover all of the generic and specific features of the invention herein described, and all statements of the scope of the 30 invention which, as a matter of language, might be said to fall therebetween.

Having described our invention, what we claim as new and desire to secure by Letters Patent, is:

1. A dispensing device comprising a container 35 adapted to change its volume to discharge its contents, means to change said volume, a closure member rotatably mounted on said container to open and close the same, and connections between said closure member and said volume 40 changing means to decrease the volume of said container by rotation of said closure member in a direction to open said container.

2. A device according to claim 1, having means to prevent operation of said volume changing 45 means until the opening movement is complete.

3. A device according to claim 1, having means to prevent reverse movement of the volume changing means during closing of the closure member and means to prevent forward motion 50 of the volume changing means until the opening movement is complete.

4. A dispensing device comprising a flexible container, a closure member rotatably mounted on said container to open and close the same, 55 means connected to the container to twist the container, to expel the contents, and means for connecting the closure member to said twisting means, to twist the container by rotary movement of the closure member to open the tube. 60

5. A device in accordance with claim 4, in which the container is substantially cylindrical, and has its lower end crimped together at the bottom and its upper end is held rigidly in a relatively larger diameter whereby on twisting said 65 twisting means, the twisting of said tube commences at the bottom.

6. A device according to claim 4, having means to prevent twisting of the container until the opening movement is complete. 70

7. A dispensing device comprising a casing, having a rotatable top, a flexible container attached to and closed by said top, a twisting means attached to the lower end of said container and non-rotatably connected to said casing, a 75

- closure mounted on said top to open and close said container and means connecting said closure to said twisting means whereby the movement of said closure to open said container will operate said twisting means to twist the container.
8. A device according to claim 7, having means to prevent operation of said twisting means by said closure until opening of the closure is complete.
9. A device according to claim 7, having means to prevent twisting of said container in either direction during the opening or closing movement of said closure.
10. A dispensing device comprising a casing, a ring rotatably mounted on said casing, a flexible container having one end non-rotatably connected to said casing and one end attached to said ring, a closure member rotatably mounted with respect to said ring and adapted by said rotation to open and close said container, including connection between said closure member and said ring whereby a rotation of said closure member will operate said ring to twist said container.
11. A device according to claim 10, having means to prevent rotation of said ring by said closure member during opening or closing of said closure.
12. A device according to claim 10, having means to prevent rotation of said ring by said closure member during opening or closing of said closure, and means to release said preventing means to permit rotation of said ring by said closure member when the opening movement is complete.
13. A dispensing device comprising a casing, having a circumferential bead at one end, a cup rotatably fitting over said end beyond said bead, a cap member fitting over said cup and crimped over said bead to fasten said cap member and said cup in place, said cup and cap member comprising elements of a closure, a flexible container within said casing having one end connected to said cup, and having its other end non-rotatably connected to said casing.
14. A device according to claim 13, having a pawl and ratchet connection between said cup shaped member and said casing to prevent rotation of said cup, when said member is rotated to close the closure.
15. A device according to claim 13, having a pawl and ratchet connection between said casing and said cup and connections between said pawl and cap member to hold said pawl in engagement with said ratchet to prevent rotation of said cup with said cap while the cap is rotated to open said closure and to free it from said engagement when the opening is complete.
16. A device according to claim 13, having a double faced ratchet on said casing, a pawl upon said cup to prevent reverse rotation of said cap, and another pawl mounted upon said cup in a direction to prevent forward motion of said cup, and a connection between said cap and said second pawl to cause said second pawl to engage said ratchet during the opening of the closure.
17. A device according to claim 13, having a double faced ratchet upon said casing, two pawls upon said cup in position to engage said ratchet, one of said pawls being spring pressed against said ratchet, and the other of said pawls being spring pressed away from said ratchet, there being a cam upon said cap in position to engage said second pawl, to force it against said ratchet when the cap is in closure closing position.
18. A dispensing device comprising a casing, a cup rotatably mounted on said casing, a closure member mounted upon said cup and cooperating therewith to form a closure, there being means to limit relative movement between said cup and closure member to that required for opening and closing the closure, a flexible container having an open end carried by and closed by said cup and having its other end closed, and non-rotatably connected to said casing.
19. A device in accordance with claim 18, having the closed end of said container crimped together of a diameter less than the open end whereby the twisting of said container commences at the bottom, except when the closure is fully open.
20. A device according to claim 18 having means for preventing relative movement between the cup and casing during said limited movement of the closure member.
21. A device according to claim 18 having means for preventing relative movement between the cup and casing during said limited movement of the closure member including a ratchet upon said casing, a pawl upon said cup and means upon the cap for forcing said pawl into engagement with said ratchet.
22. A dispensing device comprising a casing, a head rotatable upon said casing, a flexible container within said casing having an upper end attached to said head, a follower slidably within said casing and having means for preventing rotation relative to said casing and means attaching the other end of said container to said follower.
23. A device according to claim 22 in which the container is attached to said head on a materially larger diameter than its attachment to said follower.
24. A device according to claim 18 having means for preventing alternative movement between the cup and casing during said limited movement of the closure member in which the casing is formed with a longitudinal seam and the follower is provided with arms adapted to engage said rib to permit sliding movement of said follower but to prevent rotational movement thereof.
25. A device according to claim 18 having means for preventing alternative movement between the cup and casing during said limited movement of the closure member in which the casing is made of a soft material such as paper and the follower is provided with downwardly extending points which can slide upwardly but cannot rotate.
26. A dispensing device comprising a casing, a container carried by said casing and adapted to change its volume to discharge its contents, a movable element upon said casing for decreasing said volume and a ratchet element connecting said movable element with said casing to prevent reverse movement thereof, said container comprising a flexible tubular member within said casing and a movable element comprising a ring rotatable upon said casing to which the top of said container is attached and said ratchet being arranged to prevent reverse turning of said ring.
27. A dispensing device comprising a casing, a container carried by said casing and adapted to change its volume to discharge its contents,

movable element upon said casing for decreasing said volume and a ratchet element connecting said movable element with said casing to prevent reverse movement thereof, said casing having a rigid ring surrounding its upper end and rotatable thereon and said container comprising a bag of "Pliofilm" having its upper end attached to said ring and having its lower end attached to said casing and means connecting said ring with said casing.

28. A dispensing device comprising a casing of soft material such as paper, a ring rotatable

upon the upper end of said casing, a "Pliofilm" bag having its upper end attached to said ring, a follower slidable within said casing, to the lower end of which said bag is attached, said follower being provided with downwardly extending points which can slide upwardly within said casing but cannot rotate therein.

PERCY M. THORN.
